His Attorney.

UNITED STATES PATENT OFFICE.

STUART THOMSON, OF WASHINGTON, DISTRICT OF COLUMBIA, ASSIGNOR TO GENERAL ELECTRIC COMPANY, A CORPORATION OF NEW YORK.

HEATING DEVICE AND CONTROL THEREFOR.

1,350,895.

Specification of Letters Patent. Patented Aug. 24, 1920.

Application filed February 26, 1918. Serial No. 219,297.

To all whom it may concern:

Be it known that I, STUART THOMSON, a citizen of the United States, residing at Washington, District of Columbia, have invented certain new and useful Improvements in Heating Devices and Control Therefor, of which the following is a specification.

My invention relates to an electric heating device and an arrangement for controlling the temperature thereof which is simple and effective in operation.

It has hitherto been common practice when an electric heating unit was to be operated at varying temperatures, to design the unit with two separate resistance elements which were connected in series or parallel for low or high heats, respectively, medium heat being secured by connecting a single resistance element to the supply circuit. The two heating units which are required for such a system of heat control, require four terminals, and are, of course, more expensive than a single unit and more likely to get out of order.

Another disadvantage of this system of control is that the ratios of the various heats, which are as 1:½:4, are not such as are usually desired in practice. For example, the hot plates used on electric ranges commonly require for medium heat about four or five hundred watts, whereas the maximum desirable is more than twice this amount and may, for example, be 1500 watts, while it may be desirable to operate the unit at half or less than half of the wattage required for medium heat.

In accordance with my invention, a single resistance element is used in a heating unit. My invention relates to an arrangement for varying the temperature of a heating unit or a heating device, comprising a transformer, preferably an auto-transformer, and switch mechanism associated therewith for varying the number of turns of the secondary of the transformer which are included in circuit with the heating unit or units. In the case of an auto-transformer, the turns of the secondary will, of course, in part coincide with those of the primary.

In one of its aspects my invention relates to an arrangement for controlling a heating unit or units and comprises an auto-transformer connected to the heating unit in such

a way that when the heating unit or units are being supplied with full heat, the auto-transformer is not called upon to transmit any energy whatever, and does transmit energy only when the unit or units are operated at a lower heat, as for example medium or low heat, thereby making it possible to use a transformer of moderate size in a heating circuit of high wattage.

In another aspect, my invention relates to a three-wire alternating current system wherein the heating units each have one terminal connected to the neutral with the auto-transformer interposed between the supply circuit and the heating units, together with an arrangement whereby each heating unit may be connected across a supply conductor and the neutral or across any desired number of turns of the auto-transformer, so that the auto-transformer will be called upon to transmit energy only when one or more of the heating units is connected for a lower heat, and when the heating units are connected for a lower heat all of the coils of the auto-transformer are called upon to transmit energy. The most effective use is thereby made of the auto-transformer, and the temperature of each of the heating units is very nicely controlled.

For a better understanding of my invention reference may be had to the accompanying drawings in which my invention is diagrammatically illustrated, and in which Figure 1 is a view showing an element of my invention; Fig. 2 shows elements of my invention embodied in a three-wire alternating current system with an auto-transformer interposed between the heating unit, and the supply mains; and Fig. 3 shows an embodiment of my invention in a three-wire alternating current system.

Referring now to the drawings and first to Fig. 1, 10 and 11 are supply conductors across which is connected an auto-transformer 12. One terminal of a heating unit 15 is connected by a conductor 14 to one terminal of the auto-transformer, and the other terminal of the heating unit is connected to a switch 16. This switch cooperates with contacts, here illustrated as three, 18, 19 and 20 which are connected to supply conductor 10, to a tap 21 on the auto-transformer and to a second tap 22

between the tap 21 and that terminal of the transformer to which the conductor 11 is connected, respectively.

The operation of the device shown in Fig. 5 1 which will be apparent from the above description is as follows:

When "high heat" is desired in the heating unit, the switch 16 is connected to the contact 18 and the heating unit connected 10 directly across the supply circuit. The auto-transformer at this time is not called upon to transmit any power. By connecting the switch to the contact 19, the heating unit will be connected across the portion of the 15 auto-transformer between the tap 21 and the terminal of the auto-transformer to which the conductor 11 is connected, a lower voltage will be impressed on the heating device and the same will accordingly operate 20 at a lower heat, and by connecting the switch to the contact 20, a still lower voltage and lower heat will be secured. It will be obvious that by suitably arranging the 25 taps 21 and 22 and by the use of additional taps, if necessary, any desired heat ratios may be secured.

In Fig. 2 I have illustrated elements of my invention embodied in a three-wire alternating current system, an auto-transformer being interposed between the supply 30 circuit and the heating unit or units and the units being so connected to the auto-transformer that the latter will not transmit any energy when the heating unit or units 35 are connected for high heat and will be called upon to transmit energy only when the unit or units are connected for medium or low heat. In this figure I have illustrated two heating units 15 and 15^a, one terminal 40 of each of which is connected to an intermediate tap 13 on the auto-transformer which divides the same into two sections 12^a and 12^b by a conductor 14. The other terminal of the heating unit 15 is connected through 45 switch 16 and contacts 18, 19 and 20, either to the conductor 10 or to extra taps 21 and 22 of the auto-transformer in precisely the same manner as the device already described in connection with Fig. 1, while the remaining 50 terminal of the heating unit 15^a is connected through the switch 16^a and contacts 18^a, 19^a and 20^a either to the conductor 11 or to the extra taps 23 and 24 of the auto-transformer in precisely the same manner 55 as the corresponding parts associated with the unit 15.

When used in conjunction with a three-wire system, as illustrated in Fig. 2, in which the neutral is indicated by the reference character 14^a, then if either or both 60 of the units are connected for high heat, the auto-transformer will not be called upon to transmit any energy since it will be supplied by the secondary of the supply transformer (not shown in the drawing), in a

manner well understood in the art. The only time when the auto-transformer will be called upon to transmit energy will be when one or both of the units is connected to receive less than its maximum energy 70 supply with the consequence that an auto-transformer of moderate size may be connected in a circuit of high wattage.

In Fig. 3, I have shown an embodiment of my invention in which there are two sets 75 of heating units each set comprising two groups of units connected to the respective sections 12^a and 12^b of the auto-transformer. The one set which is shown in the figure as located to the left of the line 14—14^a comprises the two groups which are here represented by the single elements 15 and 15^c. The other set which is located at the right of the line 14—14^a, comprises two groups indicated by the numerals 15^a and 15^d. It 80 will, of course, be understood that each group may comprise more than a single heating unit. The heating units 15 and 15^a are connected and operated in precisely the same manner as the corresponding units 85 described in connection with Fig. 2. The other two heating units, *i. e.* 15^c and 15^d have one terminal connected by the conductor 14^a to the tap 13 of the auto-transformer. The other terminal of the unit 15^c is connected to a switch 16^c co-operating with 90 contacts 18^c, 19^c and 20^c and the other to a switch 16^d co-operating with contacts 18^d, 19^d and 20^d, respectively. The contacts 18^c and 18^d are connected to the supply conductors 10 and 11, respectively and the contacts 19^c and 19^d are connected to the taps 95 100 105 110 115 120 125 130 135 140 145 150 155 embodying a concrete structure and as operating in a specific manner in accordance with the provisions of the patent statutes, it should be understood that I do not limit my 5 invention thereto, since various modifications thereof will suggest themselves to those skilled in the art without departing from the spirit of my invention, the scope of which is set forth in the annexed claims.

10 What I claim as new and desire to secure by Letters Patent of the United States, is:

15 1. In combination; a supply circuit, an auto-transformer connected thereto, a plurality of sets of heating units connected to different sections of said auto-transformer, means for varying the energy supplied to a given unit, each set comprising two groups of units which are connected to different parts of the given section when the unit is 20 connected for less than its full energy supply.

2. The combination with a three-wire alternating current supply circuit, of an auto-transformer connected thereto, two heating 25 units connected between one supply conductor and the neutral, switch mechanism

and connections for varying the number of turns of the auto-transformer connected in circuit with each heating unit, whereby when both units are receiving energy all the 30 turns of the auto-transformer will be used in transmitting power to the heating units.

3. The combination with a three-wire alternating current supply circuit, of two sets of heating units, the sets being connected 35 on opposite sides of the neutral and having one terminal of each set connected to the neutral, an auto-transformer interposed between the heating units and the supply circuit, and means for connecting each heating 40 unit across its associated supply conductor and the neutral or across any desired number of turns of the auto-transformer, whereby the auto-transformer transmits no energy 45 unless one or more of the units is connected for a lower heat and when the units are connected for a lower heat all the turns of the auto-transformer are used in transmitting energy to the heating units.

In witness whereof I have hereunto set 50 my hand this 20th day of February, 1918.

STUART THOMSON.
